DESIGN FOR A UNIFORM SUIT

James Allen Malcolm, Cleveland, Ohio, assignor
to The Chesapeake and Ohio Railway Company,
Cleveland, Ohio, a corporation of Virginia

Application December 17, 1947, Serial No. 143,182

Term of patent 3½ years

(Cl. D3—4)

To all whom it may concern:

Be it known that I, James Allen Malcolm, a citizen of the United States, residing at Cleveland, in the State of Ohio, have invented a new, original, and ornamental Design for a Uniform Suit, of which the following is a specification, reference being had to the accompanying drawings, forming part thereof, and wherein:

Fig. 1 is a front elevation of a uniform suit embodying the design.

Fig. 2 is a rear elevation thereof.

I claim:

The ornamental design for a uniform suit, substantially as shown.

JAMES ALLEN MALCOLM.
